UNITED STATES PATENT OFFICE.

WINFIELD D. SMITH, OF DEAL, NEW JERSEY, ASSIGNOR TO KNICKERBOCKER SILVER COMPANY, OF PORT JERVIS, NEW YORK, A CORPORATION OF NEW YORK.

DESIGN FOR A METAL BORDER STRIP FOR A DISH OR SIMILAR ARTICLE.

Application filed May 28, 1923. Serial No. 6,305. Term of patent 3½ years.

To all whom it may concern:

Be it known that I, WINFIELD D. SMITH, a citizen of the United States, residing at Deal, in the county of Monmouth and State of New Jersey, have invented a new, original, and ornamental Design for a Metal Border Strip for a Dish or Similar Article, of which the following is a specification, reference being had to the accompanying drawing, forming a part thereof.

The figure is a fragmental face view of the strip showing my design, and the complete strip is a mere repetition of the parts shown.

I claim:—

The ornamental design for a metal border strip for a dish or similar article, as shown.

WINFIELD D. SMITH.
